UNITED STATES PATENT OFFICE.

LOUIS RING, OF LEESBURG, VIRGINIA.

OVERLAPPING THE EDGES OF GARMENTS.

No. 901,041.

Specification of Letters Patent.

Patented Oct. 13, 1908.

Application filed October 9, 1906. Serial No. 388,177.

To all whom it may concern:

Be it known that I, LOUIS RING, of Leesburg, in the county of Loudon and State of Virginia, have invented certain new and useful Improvements in Overlapping the Edges of Garments; and I do hereby declare the following to be a full, clear, and exact description of the invention, such as will enable others skilled in the art to which it appertains to make and use the same.

The primary object of this invention is to so form the edges or bottoms of garments that the selvage will be concealed and the parts secured without the use of linings, and not only will one side be free from all unevenness of surface, but a cuff of uniform thickness will be secured.

The invention will be hereinafter fully set forth and particularly pointed out in the claims.

In the accompanying drawings, Figure 1 is a diagrammatic view of a portion of a trouser leg, with the bottom unfolded. Fig. 2 is a similar view showing the first fold. Fig. 3 shows the second fold. Fig. 4 shows the third and final fold. Fig. 5 is a view from the side opposite to Fig. 4. Fig. 6 is an exaggerated sectional view on line 6—6, Fig. 4, showing the overlaps slightly expanded to enable the folds to be clearly understood. Fig. 7 is a similar view with the overlaps in engagement. Fig. 8 is a diagrammatic view of a portion of a sleeve. Fig. 9 shows the completed cuff.

In carrying out my invention the extreme or selvage edge 1 is folded over upon itself along the line 2, (see Fig. 2) and the material is then again folded over upon itself along the line 3 which is substantially parallel with edge 1, as shown in Fig. 3. Then, according to the depth it is desired the cuff should have, the material is, at points beyond the folded edge, twice folded upon itself, (see Fig. 4), that is, along the line 4, which is brought into parallelism with the edge of the double fold at the end of the goods, and also along the line 5, which forms the upper edge of the cuff. This latter edge is on the exterior, while the edges along the lines 2 and 4 are on the interior. The material may then be stitched together along such latter lines, as at 6, Fig. 4, or it may be pasted along such lines with rubber tissue or otherwise secured, as supposedly used in Fig. 7. In this way, not only do I secure a perfectly smooth inner surface, but there is one ply less material than in cuffs.

formed on trousers after the manner now in vogue, and the cuff is of uniform thickness so that in pressing the cuff presents a neat and uniform appearance, free from all ridges. 60 This is true both as regards cuffs for coats or shirts as well as for the legs of trousers.

In making cuffs for coats or shirts, the material may be cut in a short distance along line 5, and curved, as shown in Figs. 8 and 9, 65 the edges being stitched beyond the opening desired for the cuff. The material may be severed along the line 5, and in this way economy in material may be secured in the make up of portions of the cuff. 70

In practicing my invention in connection with coat sleeves, the linings of such sleeves may be left open at the bottom or cuff end, in which event the extreme end of the lining will be turned in and hemmed. In this way 75 the sleeve lining can be cut either the full length or shorter, and secured only at the seams of the sleeve.

The advantages of my invention will be apparent to those skilled in the art. It will 80 be seen that by means thereof the edge of fabric material may be so folded and secured as to render the use of lining unnecessary for the purpose of concealment, and also that the inner surface of the folded part is perfectly smooth. This is of special importance 85 in light weight or summer clothing. All the necessary body or stiffness is secured and at the same time a saving in material is effected and a cuff of uniform thickness, presenting a 90 smooth appearance, is secured.

I claim as my invention:

The herein described cuff for the edges or bottoms of garments, composed of material the free edge of which is twice folded upon 95 itself, with the selvage entirely inclosed and concealed, the material beyond such doubly folded portion being twice folded upon itself, to correspond in thickness with the first mentioned folded portion, one edge of the second 100 mentioned folded portion being close to the inner edge of the first mentioned folded portion, the cuffs so formed being of uniform thickness at every point.

In testimony whereof, I have signed this 105 specification in the presence of two subscribing witnesses.

LOUIS RING.
